AUTOMATIC LIFESAVING DEVICE

Jack Frankel, Brooklyn, N. Y.

Application June 10, 1946, Serial No. 675,808.

5 Claims. (Cl. 304—1)

1

This invention relates to safety devices, and more particularly to a life protector device to be used in combination with a safety belt and a cable or guy rope.

An object of the invention is to provide an automatic safety device adapted for use by a person working near a cable in an elevated position, such as on scaffolds, ships, bridges, window sills and the like, so that in the event of accident, the workman can be supported without injury and rescued from his precarious position.

Another object is to provide a safety device that can be easily and adjustably secured to a nearby cable and to a safety belt.

A further object is to provide a safety device frictionally held by cable carrying means and having cable aligning means and cable clamping means, all of novel construction.

These and other objects are accomplished in part and briefly by providing a safety device comprised of a frame, cable carrying means, cable aligning means, cable clamping means, and fastening elements whereby the device can be detachably secured to a cable and a safety belt. The cable carrying means, which forms an important part of this invention, consists of a bar hingeably joined at one end to a frame side member and releasably joined at its other end to a second frame side member. Two cable guides are mounted on the bar, one of them being movable to adjust the distance between them, and both having semi-cylindrical cuneate projecting end portions facing each other and adapted to receive between them portions of a cable wound about the bar.

A flanged projection extending outwardly from a center cross piece of the frame, aligns the downward extending portion of the cable so that it can be firmly clamped between jaws of the clamping means.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a perspective view of a safety device or automatic life protector embodying the invention herein; said device being shown used in combination with a safety belt to secure a person working on a scaffold to a guy rope.

2

Fig. 2 is a perspective view of the safety device shown in Fig. 1.

Fig. 3 is a front elevation of the safety belt shown in Fig. 1.

Figs. 4 and 5 are front and rear elevations respectively of the safety device shown in Figs. 1 and 2.

Fig. 6 is a side elevation of said device.

Figs. 7 and 8 are sectional views along the lines 10—7—1 and 8—8 respectively of Fig. 4.

Fig. 9 is a perspective view of one of the cable guide elements of the device.

Fig. 10 is a perspective view of the other of the cable guide elements of the device.

In the drawings and in the specification, in which like reference numbers designate similar parts, a safety device or automatic life protector device 15, constructed in accordance with the invention herein, is adapted for use with a safety belt such as the belt 16 shown in Fig. 3, to secure a person working in an elevated position as the person 17 shown on a scaffold 18 in Fig. 1, to a guy rope or cable 19.

The life protector device 15 is comprised of a frame 20, cable carrying means 21, cable aligning means 22, cable clamping means 23, and fastening means 24 for releasably securing the frame to the belt 16.

The frame 20 has two upright side members 25 and 25^a, a center cross piece 26 secured at its ends to the side members by bolts 27, and a bottom cross piece 28 secured at its ends to the side members by bolts 29.

The cable carrying means 21 consists of a bar 30, two brackets 31 and 31^a, and two cable guides 32 and 32^a. The bar 30 is cylindrical and has end portions 33 and 33^a of reduced transverse section disposed between arms 34 and 34^a respectively of the brackets 31 and 31^a which, in turn,

are secured by bolts 35 to the upper ends of frame side members 25 and 25^a respectively. A pin 36 extends through the bracket arms 34^a and the bar end 33^a securing them together, hingeably. A screw 37 with projecting hand 45 grips 38 extends through and threadably engages the bracket arms 34 and the rod end 33 detachably securing them together so that the bar 30 extends across and in front of the frame near its top.

The cable guide 32 (see Fig. 10) is a tube formed with a cylindrical center portion 39, a cylindrical end portion 40 of reduced transverse section, and a projecting semi-cylindrical end portion 41 with a cuneate longitudinal section in a plane normal to its axis and is adjustably po-

sitioned with the bar 30 extending through its bore 42. A key 43, resting partly in a keyway 44 extending longitudinally in the bar, and partly in a keyway 45 in the bore 42, prevents the guide 32 from turning relative to the bar, and a set screw 46, extending through the reduced end portion 40 and acting on the surface of the bar, fixes the guide 32 in position intermediate the ends of the bar, with the semi-cylindrical end portion 41 facing the cable guide 32^a.

The cable guide 32^a (see Fig. 9) is a cylindrical tube 47 with a semi-cylindrical projecting end portion 48 having a cuneate longitudinal section in a plane normal to the axis of the cylinder, and is mounted on the bar 30 near its end 33^a adjacent the frame side member 25^a, with said bar extending through the tube bore 49.

The protector device 15 is supported and frictionally held by the cable 19 which is wound or passed about the bar 30 in cable turns 50 between the cable guides 32 and 32^a, with a first half turn 51 adjacent to the center portion 39 of the cable guide 32, and a last half turn 52 adjacent the tube 47 of the cable guide 32^a. It will be noted that the semi-cylindrical cuneate end portions 41 and 48 facilitate the spiralling of the cable about the bar 30, and also wedgely fill the space opposite the half turns, increasing the frictional grip and holding the turns compactly in position. The cable guide 32 can be adjusted longitudinally on the bar 30 by means of the set screw 46 to retain the cable turns and half turns firmly in compact position.

The cable aligning means 22 is a cylindrical projection 53 extending outwardly from the front of the center cross piece 26 intermediate its ends, said projection being provided with a transverse flange 54 at its end removed from the cross piece. The projection 53 is positioned so that a portion of the cable 19 extending downwardly from the half turn 52 can rest between the flange and center cross piece at 19^a, aligning a downwardly extending cable portion with clamp jaws of the cable clamping means 23 as will appear hereafter.

The cable clamping means 23 comprises a clamp arm 55 pivotally joined intermediate its ends to a pivot 56 by a pivot pin 57, and a spring 58. The pivot 57 projects outwardly from the front of the bottom cross piece 28 being centrally disposed thereon, and the clamp arm 55 extends longitudinally in front of said cross piece. The spring 58 is positioned with its ends resting in spring seats 59 and 60 in the bottom cross piece and clamp arm respectively, and acts to retain the clamp in closed position with clamp end 61 rotated toward the cross piece, and the opposite clamp end 62 rotated away from the cross piece. The clamp end 61 has a transversely extending arcuate cut out portion or jaw 63 adapted to coact with an arcuate cut out portion or jaw 64 of a clamp piece 65 secured to the front of the bottom cross piece 28, to grip a portion of the downwardly extending aligned cable.

The fastening means 24 consists of two lines, chains or straps 66, each having a ring or link 67 at one end and a snap hook 68 at the other end. Each line 66 is secured to the frame by its ring and to the safety belt 16 by its snap hook 68, the rings extending through holes 69 and 69^a in the frame side members 25 and 25^a respectively.

The safety belt 16 has a body encircling strap 70 and two leg encircling straps 71. The strap 70 is provided with two rings 72 capable of en-

gaging the snap hooks 68 to releasably secure the safety belt to the automatic life protector device 15.

The device 15 can be installed as follows:

With the screw 37 removed and the guide 32 disassembled, the bar 30 is swung outwardly in gate fashion on the pin 36. The cable 19 can then be wound about the bar in as many cable turns 50 as is desired and the two half turns 51 and 52. The cable guide 32 is then mounted on and keyed to the rod by means of the key 43 and adjusted longitudinally to provide a compact tight assembly, after which the set screw 46 is tightened. The bar can now be swung closed with its end 33 resting between the bracket arms 34, and the screw 37 engaged to retain the bar in closed position. If it is so desired, the screw 37 can be made in the form of a removable pin. The downwardly extending portion of the cable 19 is then aligned at 19^a by placing it alongside the projection 53 between its flange 54 and the center cross piece 26. The clamp is opened by forcing the clamp end 62 toward the bottom cross piece 28 against the action of the spring 58, and the aligned cable 19 disposed between the coacting jaws 63 and 64. The user, who is provided with a safety belt such as the belt 16 having fastening elements 72, can snap the hooks 68 onto the coacting engaging elements 72.

In the event that the scaffold collapses or the user slips, he will be supported against falling by the life protector device 15 which is securely attached and clamped to the cable 19.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A safety device for a person in an elevated position near a cable and provided with a safety belt, the device comprising a frame, cable carrying means, cable clamping means and fastening elements, the frame having two side members and a cross piece extending between them, the cable carrying means consisting of a bar, hinge means, a pin and two cable guides, one end of the bar being pivotally joined to one of the side members by the hinge means, the other end of the bar being releasably secured to the other side member by the pin, each cable guide having a projecting end portion, the guides being mounted on the bar with their projecting end portions facing each other and adapted to receive between them portions of the cable wound about the bar, the cable clamping means having a clamp arm pivotally secured to the frame cross member, the clamp arm having a cut out portion adapted to grip a portion of the cable and to clamp it against the frame cross member, and the fastening elements consisting of coacting elements on the frame and safety belt capable of engaging to secure them together detachably.

2. A safety device for a person in an elevated position near a cable and provided with a safety belt, the device comprising a frame, cable carrying means, cable clamping means and fastening elements, the frame having two side members and a cross piece extending between them, the cable carrying means consisting of a bar, hinge means, a pin and two cable guides, one end of

the bar being pivotally joined to one of the side members by the hinge means, the other end of the bar being releasably secured to the other side member by a pin, each cable guide having a cuneate projecting end portion, the guides being mounted on the bar with their projecting end portions facing each other and adapted to receive between them portions of the cable wound about the bar, the cable clamping means having a clamp arm pivotally secured to the frame cross member, the clamp arm having a cut out portion adapted to grip a portion of the cable and to clamp it against the frame cross member, and the fastening elements consisting of coacting elements on the frame and safety belt capable of engaging to secure them together detachably.

3. A safety device for a person in an elevated position near a cable and provided with a safety belt, the device comprising a frame, cable carrying means, cable aligning means, cable clamping means, and fastening elements, the frame having two side members, a center cross piece and a bottom cross piece each extending between and secured to the side members, the cable carrying means consisting of a bar, hinge means, a pin and two cable guides, one end of the bar being pivotally joined to one of the side members by the hinge means, the other end of the bar being releasably secured to the other side member by the pin, each cable guide having a projecting end portion, the guides being mounted on the bar with their projecting end portions spaced from each other to receive between them portions of the cable wound about the bar, the cable aligning means comprising a projection extending outwardly from the center cross piece and having a flange at its outer end, the cable clamping means consisting of a clamp arm pivotally secured to the bottom cross piece, coacting jaws on the clamp arm and bottom cross piece adapted to grip a portion of the cable between them, and the fastening elements being positioned on the frame and safety belt and being capable of engaging to secure them together detachably.

4. A safety device for a person in an elevated position near a cable and provided with a safety belt, the device comprising a frame, cable carrying means, cable aligning means, cable clamping means, and fastening elements, the frame having two side members, a center cross piece and a bottom cross piece each extending between and

secured to the side members, the cable carrying means consisting of a bar, hinge means, a pin and two cable guides, one end of the bar being pivotally joined to one of the side members by the hinge means, the other end of the bar being releasably secured to the other side member by the pin, each cable guide having a cuneate projecting end portion, the guides being mounted on the bar with their projecting end portions spaced from each other to receive between them portions of the cable wound about the bar, one of the guides being capable of being moved along the bar to adjust the distance between the guides, the cable aligning means comprising a projection extending outwardly from the center cross piece and having a flange at its outer end, the cable clamping means consisting of a clamp arm pivotally secured to the bottom cross piece, coacting jaws on the clamp arm and bottom cross piece adapted to grip a portion of the cable between them, and a spring positioned between the bottom cross piece and the clamp arm, acting to retain the clamp jaws in closed position, the fastening elements being positioned on the frame and safety belt and being capable of engaging to secure them together detachably.

5. An escape device comprising vertical frame members, a bar connected at its ends to said members, a second bar connecting the members to each other in vertically spaced relation to the first bar, a rope guide supported between the vertical frame members, said first bar being adapted to permit a rope to be wound thereon with portions of the rope extending above and below the bar, the second bar having a fixed jaw to clamp said rope, a lever pivoted to said second-named bar in a horizontal axis to move vertically and provided with a short arm having a concave jaw to engage the rope and a long jaw, and a coil spring between said lever and the second named bar.
